UNITED STATES PATENT OFFICE.

WILLIAM H. SLEIGHT, OF ST. LOUIS, MISSOURI.

TELEPHONE ATTACHMENT.

1,316,653.

Specification of Letters Patent. Patented Sept. 23, 1919.

Application filed April 28, 1919. Serial No. 293,314.

To all whom it may concern:

Be it known that I, WILLIAM H. SLEIGHT, a citizen of the United States, residing at St. Louis, in the State of Missouri, have invented certain new and useful Improvements in Telephone Attachments, of which the following is a specification containing a full, clear, and exact description, reference being had to the accompanying drawings, forming a part hereof.

My invention relates to an improved telephone attachment, and it consists in the novel construction and combination of parts hereinafter particularly described and claimed.

The object of my invention is to provide a simple, cheap, and convenient attachment for telephone-stands, which shall be in the form of a closed casing having a hinged lid on which is suitable advertising matter, having a suitable clamping-bracket, by means of which said casing may be quickly attached to any telephone-standard (or to any other support adjacent to a telephone); the interior of said casing containing a series of alphabetically-indexed directory-cards upon which the names of persons (and their telephone numbers) that are frequently called may be written, and a memorandum-pad on the sheets of which calls and other data may be conveniently recorded; there being a pencil-holder on the exterior of said casing, as well as means for holding a pencil upon the interior of the casing when the lid or cover of the latter is closed and packed for shipping; whereby the users of telephones will be enabled to save much time, and the telephone service will be greatly facilitated.

10 In the drawings,

Figure 1 is a front-elevation of a telephone-stand having my invention applied thereto; the casing being closed to exclude dirt and dust.

15 Fig. 2 is an enlarged end-elevation of the device, detached from the phone stand, and with the casing closed.

Fig. 3 is an enlarged front-elevation of the device, with the casing closed.

20 Fig. 4 is a plan-view of same.

Fig. 5 is a front-view of the device, with the casing opened out, and all the internal parts in position for instant use.

Fig. 6 is a vertical section, taken through the device while the casing is open, on the line 6—6 of Fig. 5, and

Fig. 7 is a perspective view of a common memorandum-pad, used in the device.

In the present illustration of my invention, I have provided a casing of rectangular shape, made of pressed-steel so as to be of low cost and great durability, and composed of two sections—a body 1 and a lid 2 hinged together at their lower edges by means of suitable hinges 3.

A common spring-clip or fastener 4 has one end fixed to the upper edge of the said body 1 near the meeting-point of the body and lid, so as to extend over and frictionally engage its lug 5 on the adjacent edge of said lid, to hold the latter closed when it is not desired to use the parts upon the interior of the casing, or when same is packed for shipping.

25 A recess or indentation 6 is made in the edge of said lid, to receive the said lug.

A common pencil-holder 7 is fixed upon the right-hand end of the said body 1, to conveniently receive a pencil or other writing-instrument 8, said holder being in the form of a cylinder, with its lower end closed and its upper end open; but it is to be understood that any other form of holder may be used.

30 A long horizontal arm 9 extends across the back of the said body 1, to reinforce the same, and also to support the casing; the left-hand end of said arm 9 being extended a distance past the end of said casing and provided thereat with an integral jaw 10 of an adjustable standard-clamp; other jaws 11, 12, and 13 being adjustably arranged to form a circular-clamp for fitting around any size of standard 15, and adjustably secured together by means of common screws 14.

35 The said arm is of course fixed to the back of said casing, by means of solder or other fastening means, and when the device is attached to the telephone-standard 15 the said adjustable circular-clamp should be located a short distance below the receiver-hook 16, in order that the casing be at the proper height on said standard for convenient use.

40 A common memorandum-pad 17, com-

posed of sheets of paper having their like edges secured together in the usual manner, is located in the said body 1, and retained therein by means of over-hanging corner-brackets 18 fixed on the outer edges of adjacent sides and ends of said body by solder or other means, at one end only of said body, so as to positively prevent said pad from falling out when said body is inverted or tipped, and yet permit the pad to be removed from said casing by lifting the unconfined end of the pad out of the body first. The reverse movement is followed in placing the pad in the body, by first inserting the pad beneath said brackets 18, and then sliding the pad into place, as shown in Fig. 5.

A series of alphabetically-indexed cards 19, each being cut-away at its upper edge 20 and having one or more letters of the index on the projecting tab thereof, are located in the lid 2, and are held therein at their opposite ends by overhanging lugs or brackets 20 soldered to or formed integral with the walls of said lid, at the lower edge of the latter when it is in an open position, so that the said cards may be readily placed in position, and removed when required, and yet be prevented (by contact with the inner ends 30 of said overhanging lugs 20) from falling out when said lid is tilted or inverted.

Each of said cards 19 has printed upon its face, preferably at the upper edge, a suitable advertising matter, such as that here shown, 35 to-wit:—"R. W. Andrews Mfg. Co. Main 1540", while below said advertisement is a blank space in which may be written the names and telephone numbers of customers that are frequently called over the phone.

40 A card-tilting-device 21, made of wire bent into a substantial U-shape, and provided with a crank 22 at one end, is mounted in said lid in the rear of said cards 19, to force the upper edges of said cards outwardly to the position shown in Fig. 6, when the lid is open, whereby the upper edges of the cards may be more conveniently manipulated, in removing and replacing individual cards, or in removing the 50 entire set of cards.

By turning said crank 22 until the said card-tilting device 21 occupies the position shown in Fig. 6, the upper edges of the cards 19 will be forced outwardly to a position 55 clear of the lid, while their lower edges will be held within the lid by the said overhanging brackets or lugs 20.

Said card-tilting device 21 has its ends mounted in suitable bearings, or holes, 23 in 60 the opposite walls of said lid.

When the lid is to be closed the said card-tilting device 21 is turned down to the position indicated by the dotted lines in Fig. 6, where it lies normally in contact with the 65 back wall of the lid, when the latter is in

an open position, so as to permit the cards to rest in their normal position against said back within said lid.

The operation and use of my invention will be readily understood, without further description, except to say that the device is to be placed upon the phone standard in the position in which it is shown in Fig. 1, where it will be seen that the arm 9 extends at right-angles to the said standard 15, at a point almost diametrically-opposite the receiver-hook 16, so that the weight of the receiver will be about evenly balanced by the weight of my device, thereby preventing the stand from being so readily tipped over in 7 the direction of the receiver, which heretofore had its weight unbalanced, and caused the stand to be accidentally tipped over, frequently breaking the phone mouth-piece or some other part.

In addition to balancing the phone stand, as described, my invention when attached to the standard of the phone materially adds to the appearance of the instrument.

The outer face of the lid affords an excellent advertising space, when the lid is closed, which may be utilized by placing thereon any desired advertising matter, such for instance as that here shown, the same being as follows:

"Buy Victory Loan bonds."

"The best investment in the world."

From the above description it will be seen that my invention is a time and trouble saver, in either office or residence, or wherever the phone may be located, as it greatly facilitates the telephone service by dispensing with the time heretofore consumed in "looking up" the wanted number among the thousands of names in the telephone-book.

The memorandum-pad 17 and the pencil-holder 7 obviate the necessity of looking for a piece of paper and a pencil while the party at the other end of the line "waits" 1 during the search for writing materials with which the message can be recorded.

As an advertising medium the invention will be of the greatest value to large wholesale institutions.

I claim the following as my invention:

1. An improved telephone appliance, comprising a normally closed casing having a hinged lid upon the exterior of which is a space for advertising matter; a suitable clamping-bracket by means of which said casing may be supported upon a telephone stand; a memorandum-pad located within said casing; a card-index arranged alphabetically and located within the said lid; a card-tilting device within said lid in the rear of the rear card of said card-index, said tilting device having a crank on the exterior of said lid; and a fastening device for holding said lid closed.

2. An improved telephone appliance, comprising a normally closed casing having a hinged lid upon the exterior of which is a space for advertising matter; a suitable clamping-bracket by means of which said casing may be supported upon a telephone stand; a memorandum-pad located within said casing body; lugs attached to said body and overhanging the said memorandum-pad at one end of the latter; a card-index arranged alphabetically and located within the said lid; lugs attached to the said lid and overhanging the outermost card of the said card index at the bottom edge of the latter when the said lid is in an open position; a card-tilting device located within said lid in the rear of the rear card of said card-

index, to tilt the upper edges of the cards outwardly; means on the exterior of the said lid for operating said card tilting device from the exterior of said casing; and a fastening means for holding said lid closed when said card index and memorandum-pad are not in use.

In testimony whereof I have signed my name to this specification in the presence of two subscribing witnesses.

WILLIAM H. SLEIGHT.
